US00D973883S

(12) **United States Design Patent** (10) **Patent No.:** **US D973,883 S**
(45) **Date of Patent:** **** Dec. 27, 2022**

(54) **TRACTION PILLOW**

(71) Applicant: **Chengdu Yishouweisheng Technology Inc.**, Chengdu (CN)

(72) Inventor: **Yu Peng**, Chengdu (CN)

(73) Assignee: **Chengdu Yishouweisheng Technology Inc.**, Chengdu (CN)

(**) Term: **15 Years**

(21) Appl. No.: **29/844,203**

(22) Filed: **Jun. 27, 2022**

(30) **Foreign Application Priority Data**

Apr. 28, 2022 (CN) 202230249436.X

(51) **LOC (13) Cl.** **24-02**

(52) **U.S. Cl.**

USPC **D24/184**; D6/601

(58) **Field of Classification Search**

USPC D6/595, 596, 601, 604, 606; D24/183, D24/184, 190, 191, 215

(57) **CLAIM**

The ornamental design for a traction pillow, as shown and described.

DESCRIPTION

FIG. 1 is a front, right, top perspective view of a traction pillow, showing my design.

FIG. 2 is a rear, left, top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

1 Claim, 8 Drawing Sheets

FIG. 1

FIG. 2

FIG. 3

FIG. 4

FIG. 5

FIG. 6

FIG. 7

FIG. 8
